UNITED STATES PATENT OFFICE

123,111

DESIGN FOR A COMBINED SUNDIAL AND BIRDBATH OR SIMILAR RECEPTACLE

William G. Landon, South Lancaster, Mass.

Application July 20, 1940, Serial No. 93,817

Term of patent 3½ years

To all whom it may concern:

Be it known that I, William G. Landon, a citizen of the United States, residing at South Lancaster, in the county of Worcester and State of Massachusetts, have invented a new, original, and ornamental Design for a Combined Sundial and Birdbath or Similar Receptacle, of which the following is a specification, reference being had to the accompanying drawing, forming a part thereof, in which

Figure 1 is a plan view of a combined birdbath and sundial showing my new design; and

Figure 2 is a side elevation of the article shown in Fig. 1 at approximately right angles to the bird.

The dominant feature of this design is a receptacle with a bird mounted on a perch rising from said receptacle at such an angle that it forms a gnomon cooperating with graduations on the rim of the receptacle to operate as a sundial.

I claim:

The ornamental design for a combined sundial and birdbath or similar receptacle, substantially as shown and described.

WILLIAM G. LANDON.
